UNITED STATES PATENT OFFICE

ROBERT LEE GRAY, OF JERSEY CITY, NEW JERSEY

VALVE OPERATING MECHANISM

Application filed March 29, 1929. Serial No. 351,064.

The present invention relates to a valve operating mechanism particularly adapted for internal combustion engines. It is an object of this invention to construct the valve or valves of each cylinder so that they shall be mechanically or positively opened and mechanically or positively closed and at the same time rotated, thereby accomplishing a positive opening and closing, as well as a positive seating of the valve. The rotation of the valve, even though slight, eliminates the necessity of grinding the valve and valve seat since they are kept true with each other at all times and prevent the formation of carbon on the seating surfaces.

It is a further object of this invention to place the mechanical operating mechanism of the valves at the side thereof, that is, adjacent to the sides thereto so that the expansion and wear of the valve will not interfere with the opening and closing thereof. A still further object of the invention resides in the specific cam construction located adjacent to the side of the valve or the valve stem to suitably operate the valve.

Still further objects will be apparent from the following description taken in connection with the accompanying drawings in which the same reference characters indicate corresponding parts throughout and in which:

Figure 1 is a vertical cross section of a cylinder of an internal combustion engine showing the valve mechanism,

Fig. 2 is a top view of the cylinder of Fig. 1,

Fig. 3 is a cross section of a portion of a cylinder of an internal combustion engine showing a modified valve operating mechanism,

Fig. 4 is a vertical cross section of a further modified valve operating mechanism,

Fig. 5 is a side view of the separate cams for actuating the valve of Fig. 4,

Fig. 6 is a top view of one of the stationary cams of Fig. 5, and

Fig. 7 is a top view of the movable cam of the valve of Fig. 5.

The valve operating mechanism, as well as the valves, is shown as applied to cylinder 1 of an internal combustion engine. The usual piston 2 is provided in the cylinder, as well

as a spark plug 4 which is placed in any desired location. At the top of the cylinder, the head 34 is suitably secured in and on the cylinder by means of suitable bolts 35. Each cylinder is provided in its wall with an intake port 5 and an exhaust port 6 preferably arranged in opposite relation, which ports cooperate with suitable passages 36 in the head 34. The lower end of each passage 36 terminates in a valve seat 37 and the passage is divided in the central portion of the head by means of a partition 38. The valves 3, preferably two in number, are provided in the head and at the upper end of the stem 39 a cam member 14 is secured which has a screwthreaded portion 16 at the lower end and cam projections 17 at the upper end. The screwthreaded portion 16 cooperates with suitable screwthreads 15 in the head 34 and the central portion of the cam member 14 has a cylindrical bore 51 therein. A spring 13 is provided in the bore 51 and around the valve stem, bearing at one end on the head 34 and the other end against the cam member. An enlarged portion 12 in the upper end of the valve stem secures the valve stem in the cam member and also provides for the rotation of the valve when the cam member is rotated.

The valves are actuated by means of a plurality of cams 18 and 19 mounted to rotate on a shaft 10 which is suitably mounted in bearings 40 on the top of the cylinder head. The shaft 10 receives its rotation from the shaft 7 through bevel gears 8 and 9 and the shaft 7 is suitably rotated from the crank shaft of the engine. As clearly shown in Fig. 2 of the drawings, the valve is actuated by rotating the cam portion 14, which is accomplished by the rotation of the shaft 10 causing the cams 18 and 19 to contact with one projection 17 and then the other to oscillate the cam portion 14. As the cam portion 14 is rotated, it is forced axially upwardly or downwardly, as the case may be, due to the screwthreaded portions, which thereby open and close the valve. The spring 13 is for the purpose of providing for a tight closure to take up a slight clearance between the projections 17 and the cams 18 and 19, the

cams furnishing a positive opening as well as a positive closure of the valve and also a rotation of the valve on its seat.

In the modification according to Fig. 3, 5 the cam member 14 of the valve 3 is rotated by means of stems 23 which take the place of the cams 18 and 19. The stems 23 are actuated by pivoted elbows 25 which are actuated by the sliding stems 26, said sliding stems in turn being suitably operated from the cam shaft of the engine, for instance. The stems 23 slide in the support 24 which is preferably an integral portion of the cylinder head 34. The operation of the valves is, of course, the same as that shown in connection with Figs. 1 and 2.

Fig. 4 shows a construction in which the valves are placed adjacent the cylinder and not in the head as in the modifications according to Figs. 1-3. The passage 41 communicates with the inner chamber of the cylinder and is closed by a top member 42 suitably bolted to the engine block by means of bolts 35. A central opening 43 in the top member can be screwthreaded to accommodate a spark plug. The valves 44 are provided in the cylinder block 45, which block is supplied with valve seats 46 for the valves. The stems 39 of the valves project downwardly and on the intermediate portion of the stem a collar 28 is secured which has external screwthreads 47 arranged in the periphery thereof. This collar is adapted to be rotated by means of the screwthreads 30 on the shaft 31 which mesh with the threads 47. The shaft 31 rotates in suitable bearings 48 in the engine block and is in turn rotated from the crank shaft of the engine. In both of the end faces of the collar, as clearly shown in Fig. 5, a number of projections or cam portions 49 are provided which may comprise any suitable number. For purpose of illustration, three such cams at each end have been shown, these cams cooperating with corresponding cam portions 50 on the stationary collars. The upper collar 27 is suitably secured in the block 45 so as to be non-rotatable and the lower collar 29 is also non-rotatably held in place by means of the retaining member 51 which is suitably bolted to the engine block. The central portion of the collars is provided with a bore 54 in which a spring 33 is placed in order to compensate for any wear and any clearance provided between the cam members.

As is clearly evident from Fig. 4, it may be seen that by rotation of the shaft 31, the screwthreads 30 will rotate the collar 28 which will result in a rotary movement of the valve, as well as an oscillating movement thereof due to the cam members 49 cooperating with the cams 50 of the stationary collars 27 and 29. This not only provides for a positive opening and closing of the valve 65 but also a rotary motion thereof. Fig. 4 at

the left shows the valve in open position, the cams of collars 27 and 28 coinciding and the cams of 29 and 28 opposing each other.

I claim as my invention:—

1. A valve operating mechanism for internal combustion engines comprising a cam member provided around a stem of the valve and having a lower screwthreaded portion and a pair of cam projections at the upper portion; a head in which the valve actuates and having screwthreads cooperating with the screwthreaded portion of the cam member; and a pair of cams one cooperating with one cam projection to open the valve and the other cam cooperating with the other cam projection to close the valve, said screwthreads and screwthreaded portion providing for a rotary motion of the valve when actuated axially by the cams. 70

2. A valve operating mechanism for internal combustion engines comprising a cam member provided around a stem of the valve and having a lower screwthreaded portion and a pair of cam projections at the upper portion; a head in which the valve actuates and having screwthreads cooperating with the screwthreaded portion of the cam member; a pair of cams one cooperating with one cam projection to open the valve and the other cam cooperating with the other cam projection to close the valve; and means for actuating the cams to axially actuate the valve and cause rotation thereof due to the screwthreads. 85

3. A valve operating mechanism for internal combustion engines comprising a cam member provided around a stem of the valve and having upper cam projections and a lower screwthreaded portion; a head in which said valve and stem is mounted and having a screwthreaded portion cooperating with the screwthreads on the cam member; and a stem for each cam projection slidably mounted on the head and adapted to positively open and close the valve and also rotate said valve by means of the screwthreads. 100

4. A valve operating mechanism for internal combustion engines comprising a cam member provided around a stem of the valve and having upper cam projections and a lower screwthreaded portion; a head in which said valve and stem is mounted and having a screwthreaded portion cooperating with the screwthreads on the cam member; a stem for each cam projection slidably mounted on the head and adapted to positively open and close the valve and also rotate said valve by means of the screwthreads; and an elbow for each stem to impart the sliding motion thereto. 115

5. A valve operating mechanism for internal combustion engines comprising a cylinder block having a screwthreaded portion therein; a valve and stem provided in the block and having a rotary collar secured on 130

the stem which is provided with screwthreads cooperating with the screwthreads in the block, said collar having cam portions at each end thereof; a pair of stationary collars 5 mounted in said block and around said stem one on each end of the rotary collar, said stationary collars having cam portions thereon corresponding to the cam portions on the rotary collar; and means for imparting 10 a rotary motion to the rotary collar thereby rotating the valve and imparting an axial back and forth movement to the valve to positively open and close said valve.

6. A valve operating mechanism for internal combustion engines comprising a cylinder block having a screwthreaded portion therein; a valve and stem provided in the block and having a rotary collar secured on the stem which is provided with screwthreads 15 cooperating with the screwthreads in the block, said collar having cam portions at each end thereof; a pair of stationary collars mounted in said block and around said stem one on each end of the rotary collar, said stationary collars having cam portions thereon corresponding to the cam portions on the rotary collar; and a screwthreaded shaft arranged in said block and cooperating with the screwthreads on the rotary collar to im- 20 part a rotary motion to the rotary collar thereby rotating the valve and imparting an axial back and forth movement to the valve to positively open and close said valve.

In testimony whereof I affix my signature.
